US0D1035291S

(12) **United States Design Patent** (10) **Patent No.:** **US D1,035,291 S**
(45) **Date of Patent:** **** Jul. 16, 2024**

(54) **SEATING**

(71) Applicant: **Exemplis LLC**, Cypress, CA (US)

(72) Inventors: **Richard Joutras**, Oak Brook, IL (US);
Timothy Buchenberger, Oak Brook, IL (US)

(73) Assignee: **Exemplis LLC**, Cypress, CA (US)

(**) Term: **15 Years**

(21) Appl. No.: **29/745,830**

(22) Filed: **Aug. 10, 2020**

Related U.S. Application Data

(63) Continuation of application No. 29/650,968, filed on Jun. 11, 2018, now Pat. No. Des. 895,315.

Primary Examiner — Karen S Acker

(74) *Attorney, Agent, or Firm* — Knobbe, Martens, Olson & Bear LLP

(57) **CLAIM**

The ornamental design for a seating, as shown and described.

DESCRIPTION

FIG. 1 is a top, front, and right-side perspective view of a seating;

FIG. 2 is a bottom, rear, and left-side perspective view thereof;

FIG. 3 is a front view thereof;

FIG. 4 is a rear view thereof;

FIG. 5 is a left-side view thereof;

FIG. 6 is a right-side elevational thereof;

FIG. 7 is a top view thereof; and,

FIG. 8 is a bottom view thereof.

The broken lines and unshaded areas are used to illustrate portions of the seating that form no part of the claimed design.

1 Claim, 8 Drawing Sheets
